UNITED STATES PATENT OFFICE

136,900

DESIGN FOR A TIE RACK

Clarence W. Jorgensen and William A. Odencrantz, Chicago, Ill.

Application April 3, 1943, Serial No. 109,900

Term of patent 3½ years

To all whom it may concern:

Be it known that we, Clarence W. Jorgensen and William A. Odencrantz, citizens of the United States and residents of Chicago, in the county of Cook and State of Illinois, have invented a new, original, and ornamental Design for a Tie Rack, of which the following is a specification, reference being had to the accompanying drawing, forming a part thereof.

In the drawing:

Figure 1 is a front elevational view of a tie rack, showing our new design;

Fig. 2 is a top plan view;
Fig. 3 is a rear elevational view; and
Fig. 4 is an end elevational view thereof, on an enlarged scale.

We claim:

The ornamental design for a tie rack, substantially as shown.

CLARENCE W. JORGENSEN.
WM. A. ODENCRAVTZ.
